THREAD-GUIDE CONTROL FOR BOBBIN-WINDING MACHINES

Woldemar Heinitz, Chemnitz, Germany, assignor to Schubert & Salzer Maschinenfabrik Aktiengesellschaft, Chemnitz, Germany

Application March 17, 1932, Serial No. 599,504
In Germany April 30, 1931

2 Claims. (Cl. 242—31)

My invention relates to thread-guide controls for bobbin-winding machines.

It is an object of my invention to provide a control for the winding of conical or bottle bobbins in which the bobbin consists of individual layer sets, which is more adaptable than the usual control. To this end, in combination with mechanism for moving a thread guide along a peg, I provide means for temporarily reversing the direction in which the mechanism operates. By these means I obtain superimposed layer sets which are not uniform but partly cross-wound, without additional undulation.

In a preferred embodiment of my invention I equip the usual cam for reciprocating the thread-guide plate with steps, so that the reciprocation of the thread-guide plate is temporarily reversed by the steps.

In the drawings affixed to this specification and forming part thereof a control embodying my invention is illustrated diagrammatically by way of example.

In the drawings

Fig. 1 is a sectional elevation of a control having a cam according to the invention,

Fig. 2 is a front end elevation of the control, viewed from the left in Fig. 1, and

Fig. 3 is a plan view of the control.

Fig. 4 is an elevation of a bottle bobbin,

Fig. 5 is an elevation of a conical bobbin, and

Fig. 6 is a diagram drawn to a larger scale and showing the winding of the bottle bobbin in Fig. 4.

Referring now to the drawings and first to Figs. 1 to 3, A is the frame of the machine, 4 is its driving shaft, 3 is a vertical friction disk on the driving shaft, and 2 is a horizontal friction disk of smaller diameter on the vertical shaft 1 of a conical peg or pin 3, which horizontal disk 2 bears on the vertical disk 3 by gravity.

9 is the control shaft to which rotation is imparted by reduction gearing 5, 7, 6, 8, 10. The wheels of the reduction gearing are disposed in a plane which is in front of the plane on which Fig. 1 is sectioned and are therefore shown as circles in dot-and-dash lines. 11 is a cam on the shaft 9, 12 is a push rod with a roller at its lower end for cooperation with the cam 11 and 13 is the thread-guide plate at the upper end of the push rod 12.

14 is a threaded spindle on the thread-guide plate, 15 is a spur gear which is mounted on the spindle 14 with its internally threaded hub, and 16 is a thread-guide on the hub. The thread is indicated in dot-and-dash lines in Fig. 1.

31 is an elongated pinion or serrated shaft which is mounted in a bearing on a bar extending

longitudinally along the top of the frame A and extends in parallel to the threaded spindle 14. Rotation is imparted to the pinion 31 by bevel gearing 29, 30 and a shaft 27.

28 is a sprocket on the outer end of the shaft 27, 32 is a sprocket of equal diameter on the boss of a ratchet wheel 24 which is mounted to rotate on a pin 21, and 26 is a chain on the two sprockets.

17 is an eccentric on the control shaft 9 and 18 is its rod. The rod 18 engages a pin in the slotted free end of a lever 19 which is mounted to rock about a pin 21. 20 is a short arm extending from the lever 19, 23 is a ratchet pawl on the free end of arm 20 which engages in the ratchet wheel 24, and 22 is a threaded check for adjusting the pawl 23.

As the control shaft 9 rotates the lever 19 and the arm 20 are rocked about the pin 21 by the eccentric 17, imparting intermittent rotation to the ratchet wheel 24. The rotation is transmitted to the pinion 31 by the sprockets, chain and bevel gears described. Rotation of the pinion 31 causes the spur gear 15 to rotate and to move along the thread of the spindle 14. The amount through which the spur gear and the thread guide 16 are displaced on the spindle 14 is regulated in conformity with the thickness of the thread by adjusting the teeth 23 through the medium of the check 22 so that the ratchet wheel 24 is rotated through a corresponding number of teeth per stroke of the arm 20.

As shown in Fig. 1 the cam 11 has a uniform rising curve extending through an angle b and a trailing curve extending through an angle c which is stepped at d , e , f , and g . The uniform rising curve is limited at one end by the longest radius R and at the other end by the shortest radius r of the cam. The radii are determined in conformity with the length a of a layer on the peg B, Fig. 6. The radial distances of the steps d , e , f , g of the cam 11 from the center of the shaft 9 progressively decrease from the highest point of the uniform rising curve to the lowest point of said curve. That is to say, the radius of step d is greater than that of step e , the radius of step e is greater than that of step f , and the radius of step f is greater than that of step g .

In Fig. 4 the length a is shown on a bottle peg C, and in Fig. 5 it is shown on the conical peg B illustrated in Fig. 1.

The control shaft 9 and the cam 11 rotate anti-clockwise as indicated by the arrow in Fig. 1, reciprocating the push rod 12 and the thread-guide plate 13. Fig. 1 shows the position of the

- cam 11 in which the shortest radius r is in line with the axis of the push rod 12. The push rod is now raised gradually and uniformly by the rising curve corresponding to the angle b until 5 the longest radius R is in line with the axis of the push rod 12. The movement of the thread guide 16 is the resultant from the movement imparted to it by the radius $R-r$ and the movement it performs on the threaded spindle 14 10 while being rotated by the pinion 31 and its spur gear 15. Uniform movement of the thread guide through the distance a winds a layer on the peg which has parallel and uniform helical windings as shown for the bottle peg C in dotted lines in 15 Fig. 6. This uniform layer is completed when the thread guide 16 has arrived at the upper end of its stroke a . The stepped trailing curve corresponding to the angle c now cooperates with the roller at the lower end of the push rod 12 20 while the push rod descends by gravity. The co-operation of the stepped trailing curve with the push rod 12 effects a movement of the thread guide 16 to a certain amount in one direction and a smaller amount in the reverse direction, 25 that is to say, a so-called pilgrim movement. The effect of this pilgrim movement is that uniform windings are formed while the cam 11 rotates from the end of the longest radius R to the first step d by which the descent of the push rod 30 12 is temporarily reversed into an ascending movement, as indicated by the zig-zag line at d in Fig. 6. This results in cross-windings for the range of the step d . At the end of the step d the push rod continues its descent until it is reversed 35 again by the second step e , and so on, until finally the shortest radius r is again in line with the axis of the push rod 12 and the cycle is completed. It will appear that at each step a small additional movement is superimposed on the uniform movement of the thread guide. In this 40 manner the pilgrim movement of the thread guide 16 is obtained, that is to say, the movement of said thread guide 16 is temporarily reversed and cross windings are formed. Fig. 6 includes 45 a diagram showing the small additional reversing movements imparted by the steps d, e, f, g and the cross windings resulting therefrom. The reversing movement is indicated by the zig-zag arrow.
- 50 I claim:—
1. In a thread guide control for bobbin-winding machines, a thread guide, a rotary peg for a bobbin, a main shaft driving said peg, a cam shaft driven by said main shaft, a cam on said
- cam shaft having a uniformly shaped rising curve and a trailing curve, said rising curve during the rotation of said cam imparting a uniform and complete upward stroke to said thread guide, a plurality of steps formed in said trailing curve the radial distances of which from the center of said cam shaft progressively decrease from the highest towards the lowest point of said uniformly shaped curve whereby a descending stroke with a pilgrim movement will be transmitted to said 10 thread guide, each irregular traversing movement effected by said descending stroke being of an upward stroke less than that of the complete upward stroke of the thread guide effected by said uniformly rising curve of said cam and a downward stroke less than that of each upward stroke and means driven by said cam shaft for varying the position of said thread guide relative to its position caused by said cam. 15
2. In a winding machine for producing conical or bottle bobbins with overlapped or interlocked layers of thread comprising in combination a rotary peg, a thread guide associated therewith, a driven shaft for rotating said peg, a cam carried by said shaft, means for operatively connecting said thread guide with said cam, said cam having a uniformly shaped rising curve and a trailing curve for imparting traversing strokes to said thread guide whereby upon each revolution of said cam said rising curve will impart a uniform and complete upward stroke to said thread guide and said trailing curve permitting descending strokes for producing layers of thread of different sizes, a plurality of steps formed in said trailing curve whereby during each descending stroke of said thread guide irregular traversing movements will be transmitted to said thread guide over each layer of threads so formed as to produce the overlapped or interlocked layers of thread in each layer, each irregular traversing movement of the thread guide being of an upward stroke less than that of the complete upward stroke of the thread guide and that of each proceeding irregular traversing movement and the down stroke of each irregular traversing movement being greater than that of the proceeding traversing movement and less than that of the completed down stroke of the thread guide, and means operatively connecting said driven shaft with said thread guide to vary the position 30 of the latter with respect to its positions caused by said cam. 35
